UNITED STATES PATENT OFFICE.

CYRUS M. CARNAHAN, OF ALLEGHENY, PENNSYLVANIA.

CAR-TRUCK.

SPECIFICATION forming part of Letters Patent No. 694,942, dated March 11, 1902.

Application filed February 20, 1901. Serial No. 48,185. (No model.)

To all whom it may concern:

Be it known that I, CYRUS M. CARNAHAN, a citizen of the United States of America, and a resident of Allegheny, county of Allegheny, State of Pennsylvania, have invented certain new and useful Improvements in Car-Trucks, of which the following is a specification, reference being had to the accompanying drawings, forming part of this specification, in

10 which—

Figure 1 is a side elevation of my improved car-truck. Fig. 2 is a plan view thereof, partly in section. Fig. 3 is a detail view illustrating a modification providing for a 15 lower bolster-bearing. Fig. 4 is a longitudinal view indicated by the line IV IV of Fig. 2, showing the interior faces of the truck. Fig. 5 is an inner view, partly in section, indicated by the line V V of Fig. 2. Fig. 6 is 20 a transverse sectional view indicated by the line VI VI of Fig. 2. Fig. 7 is a similar detail view indicated by the line VII VII of Fig. 4. Fig. 8 is a cross-sectional view indicated by the line VIII VIII of Fig. 4. Fig. 9 25 is a sectional detail view illustrating the modification shown in Fig. 3 and at a right angle thereto. Fig. 10 is a detail view of one end of one of the side members, illustrating a construction wherein the journal-box is removed 30 vertically. Fig. 11 is a detail view illustrating the manner of suspending the brake-shoe.

My invention relates to the class of car-trucks, more especially to trucks composed entirely of metal; and it consists of the novel 35 construction and arrangement of the parts, as will be more fully hereinafter set forth.

Referring to the drawings, the main side member of the truck is composed of a channel-beam 2, the flanges 3 of which project 40 outwardly, such channels extending for the full length of the truck. Midway of the truck, below channel 2, is a similar channel 4, the ends of which terminate at the inner sides of the journal-boxes 5 and constitute, with the 45 reinforcing members, the inner journal-box housings, and such lower channel, as will be seen, is of the same depth as the journal-box. The lower edges of the upper channel 2 likewise constitute, with the supplemental reinforcing members, the upper bearing edges of the journal-box housings. The length of the 50 lower channel 4, as will be seen, corresponds

to the distance between the journal-boxes, and a lower supplemental plate or bar member 6 is secured to the lower channel 4 and 55 to the reinforcing members and extends at each end beyond the ends of the channel 2, thus providing lower inclosing sides for the journal-box housings. This member 6, which I have shown as a bar, may, as is obvious, 60 consist of any other suitable shape, as a channel, angle, I-beam, &c. The remaining outer inclosing side of the journal-box housings consists of a short section 7, preferably made of I-beam or other suitable shape, the inner 65 bearing edges of which are provided with reinforcing-angles 8. The section 7 is made removable for insertion or removal of the wheels, axles, and journal-boxes and is held in position by bolts 9, which pass through 70 the member 6, flanges of member 7, and flanges and reinforcing members of the upper channel 2.

In Fig. 10 I have shown a modified construction wherein the section 7 is rigidly incorporated with the under outer end of member 2 by riveting, as shown, and the end of member 6 is made to consist of a separate removable section 6", which constitutes the lower housing of the journal-box. This removable section 6" is held in position by bolts 9 at each side, as shown, passing through the flanges of the main members and of their reinforcing members, by which means when the bolts are tightened the journal-box is securely retained in position by the section 6" and all of the parts are firmly connected together. This construction is available and of advantage when it is desired to insert or remove the journal-box vertically, as by lowering it from the truck or jacking the truck up from it. The upper and lower channels are reinforced by horizontal angle members 10 and vertical angle members 11, firmly riveted to the channel members and providing 95 by their flanges supplemental flange members corresponding to the flange members of the channel.

Midway of the truck, extending across it, resting upon members 6, and connected thereto and with the channel 4 by rivets and angles 12, is a transverse bolster-support, which I have shown as being composed of a channel 13, which provides a good bearing for the

bolster-springs and is rigidly connected to the opposite member of the truck.

Above the sides of the support 13, upon the inner face of each side member, are secured 5 vertical angle members 14, connected to channels 2 and 4 by rivets and providing suitable bearings for each end of the bolster 15, as clearly shown in Figs. 2 and 4.

On each side of the bolster-support, extending 10 from one side member to the other, are transverse brace members 16, which I have shown as being composed of channels connected to both channels 2 and 4 by rivets and angle-brackets 17. A feature of importance 15 of these cross members 16 is that they are slantingly disposed, as clearly shown in Figs. 1 and 4, whereby the upper edge projects outwardly over the lower edge, corresponding approximately to the line of contour of the 20 wheels, and a particular advantage of this construction is in the facility whereby the brake-beams are supported from such cross members 16 as thus disposed, the attachment being made directly to the web of the channel, and whereby it is vertically above the 25 point of suspension of the brake-beam, adjacent to the wheel periphery, as I have indicated in the dotted lines in Fig. 4. A further advantage of this construction is in the great 30 bracing strength of the end members 16, they approximating positions between the vertical and horizontal, and thereby offering great resistance to torsional strain, while, as will be seen, the connections of the upper ends with 35 the side members are more distant from each other than the lower ends, and both connections are sufficiently far apart to constitute, with the side members, a rectangular brace of great strength and rigidity, whereby the efficiency of the truck is enhanced. While I 40 prefer the slanting arrangement, good results may be had by arranging the brace members 16 vertically or at other angles than that shown, and I do not desire to be confined to 45 the construction set forth. As thus constructed my improved truck is very compact, comparatively light in weight, composed of parts that may be cut to length of merchant-rolled-steel shapes, and it is generally well 50 adapted to the objects in view. The inner faces of the main channel members 2 and 4 being unobstructed by flanges or rivets provide a good bearing-surface for the ends of the bolster, which fit snugly against them between the angles 14. When for any reason 55 it is desired to provide a lower bearing for the bolster, a supplemental member 18 may be attached to the lower side of the channel 4, the member 6 in such case being lowered 60 around it in the form of a truss 6', as clearly shown in Figs. 3 and 9, in which construction the angles 14 are extended down, connecting the members 4 and 18, and the bolster-support 13 rests upon the bar extension 6' and 65 is likewise secured to member 18 by angles 12 and riveted.

While I have shown the various parts of

the truck as being composed of structural sections which are well adapted to be incorporated with the truck as I have designed it, it is clear that other sections or shapes may be substituted by the skilled mechanic within the scope of the following claims, and I do not therefore desire to be limited to the exact construction as shown and described, but to include all such changes and variations therefrom as would be within the province of the skilled mechanic.

Having described my invention, what I claim is—

1. In a car-truck, a side member composed of an upper structural member for its full length, a lower structural member connected therewith, terminating at and forming the inner sides of the journal-box housings, supplemental end members forming the outer sides of the journal-box housings, and a lower member forming the lower sides of the journal-box housings.

2. In a car-truck, a side member composed of an upper structural member for its full length, an intermediate lower structural member terminating at and forming the inner sides of the journal-box housings, a lower member extending for the full length forming the lower sides of the journal-box housings, and intervening removable end sections forming the outer sides of the journal-box housings.

3. In a car-truck, a side member composed of an upper channel member for its full length, an intermediate channel member terminating at and forming the inner sides of the journal-box housings, a lower plate member extending for the full length forming the lower sides of the journal-box housings and intervening removable I-beam end section forming the outer sides of the journal-box housings.

4. In a car-truck, a side member composed of an upper channel member for its full length, an intermediate channel member terminating at and forming the inner sides of the journal-box housings, a lower plate member extending for the full length forming the lower sides of the journal-box housings, and intervening removable I-beam end sections forming the outer sides of the journal-box housings, with means for connecting the members, substantially as set forth.

5. In a car-truck, a side member composed of an upper channel member for its full length, an intermediate channel member terminating at and forming the inner sides of the journal-box housings, a lower plate member extending for the full length forming the lower sides of the journal-box housings, intervening removable I-beam sections forming the outer sides of the journal-box housings and supplemental angle members riveted to and connecting the members, substantially as set forth.

6. In a car-truck, a side member composed of an upper channel member for its full length, an intermediate channel member terminating

at and forming the inner sides of the journal-box housings, a lower plate member extending for the full length, forming the lower sides of the journal-box housings, intervening removable I-beam end sections forming the outer sides of the journal-box housings, supplemental angle members riveted to and connecting the members, and end bolts connecting the removable end sections with the upper and lower members, substantially as set forth.

7. In a car-truck, a side member composed of an upper channel member for its full length, an intermediate channel member, terminating at and forming the inner sides of the journal-box housings, a lower plate member extending for the full length forming the lower sides of the journal-box housings, intervening removable I-beam end sections forming the outer sides of the journal-box housings, supplemental members riveted to and connecting the members, vertical guiding angle members for the bolster riveted to the inner plane side of the upper and intermediate channel members, and end bolts connecting the removable end sections with the upper and lower members, substantially as set forth.

8. A car-truck composed of sides comprising upper structural members, intermediate structural members terminating at and forming the inner housing-walls, lower members inclosing the journal-boxes, and outer end sections, with cross connecting members providing a bolster-support, substantially as set forth.

9. A car-truck composed of sides comprising upper structural members, intermediate structural members terminating at and forming inner housing-walls, lower members inclosing the journal-boxes, removable end sections, with a cross connecting member providing a bolster-support, and supplemental cross connecting members, substantially as set forth.

10. A car-truck composed of sides comprising upper structural members, intermediate structural members, terminating at and forming inner housing-walls, lower members inclosing the journal-boxes and removable end sections, with a cross connecting member providing a bolster-support, and supplemental cross connecting bracing members tilted outwardly and providing brake-beam supports, substantially as set forth.

11. In a car-truck of the class described, cross connecting and bracing members consisting of channel-bars, rigidly connected at each end to the side members, and tilted outwardly whereby the upper flange projects beyond the lower flange for the purposes as set forth.

12. A car-truck composed of sides comprising upper structural members, intermediate structural members terminating at and forming inner housing-walls, lower members inclosing the journal-boxes removable end sections, angle members riveted to and connecting the members and forming vertical bolster-guides, and a cross connecting member, providing a bolster-support, substantially as set forth.

13. A car-truck composed of sides comprising upper structural members, intermediate structural members, terminating at and forming inner housing-wall, lower members inclosing the journal-boxes, removable end sections, angle members riveted to and connecting the members and forming vertical bolster-guides, a cross connecting member providing a bolster-support, and supplemental cross connecting and bracing members on each side of such members, substantially as set forth.

Signed at Pittsburg this 4th day of December, 1900.
